UNITED STATES PATENT OFFICE.

CHAUNCEY B. PLATT, OF VANMETER, IOWA.

BRICK-KILN.

SPECIFICATION forming part of Letters Patent No. 718,022, dated January 6, 1903.

Application filed March 24, 1902. Serial No. 99,687. (No model.)

To all whom it may concern:

Be it known that I, CHAUNCEY B. PLATT, a citizen of the United States, residing at Vanmeter, in the county of Dallas and State of 5 Iowa, have invented new and useful Improvements in Brick-Kilns, of which the following is a specification.

My invention has relation to improvements in brick-kilns of that build or construction 10 denominated "downdraft-kilns;" and the object is to construct a kiln provided with floor-flues leading into a cross-flue and a central sectional portion, from whence parallel draft-flues provided with dampers lead to the stack, 15 whereby the draft may be so regulated that the caloric effects may be regulated and limited to certain and different portions of the material in the kiln.

With the foregoing-stated objects in view 20 the invention consists in the improved construction of parts and their arrangement and aggroupment in operative combined and improved results.

I have fully and clearly illustrated the invention in the accompanying drawings, forming 25 a part of this specification, and wherein—

Figure 1 is a longitudinal vertical section through the kiln, showing the floor construction and central flue leading to the stack, the 30 illustration being taken on the line 1 1 of Fig. 2. Fig. 2 is a horizontal section parallel with the floor-flues, showing the transverse channel or flue, the central circular or angular passage or flue, and the arrangement of 35 the furnaces. Fig. 3 is a horizontal section similar to that seen in Fig. 2, except that the central passage is shown circular instead of angular.

Referring to the drawings, A designates the 40 wall of the kiln, made of suitable material and of such height and to inclose such space as may be requisite to give the required capacity to the kiln. The kiln may be of any desired contour in cross-section. I have illustrated it as round and covered with an arched and rounded roof 1, in which are made windows 2, utilized for the purpose of examining the ware and to permit the escape of smoke in the preliminary stages of combustion. The 45 windows are provided with any suitable closures, as 3, which cover them when desirable.

4 designates the furnaces, of any proper

construction, built in the wall of the kiln at determined distances apart and are formed with vertical flues 5, the walls of which are 55 sealed to or built in the masonry of the kiln-wall and reach to such heights as to throw the products of combustion over the contents of the kiln, as indicated by the arrows extending from the tops of said flues. A door 60 6 is provided whereby access to the interior of the kiln is had.

On a proper foundation constituting a floor within the base of the kiln are laid a plurality of partitions 7, parallel with each other 65 and forming the side walls of the floor-flues and extending across the interior of the kiln and also extending over and bridging transversely-arranged draft-flues 8 8^b and an angular or circular flue 9, into which the draft-flues 8 8^b open at their inner ends. Over the floor-flues 7 are laid bricks 10, either having interstices between them for the escape of the gases into the floor-flues or made with recesses, through which the gases pass. In the 70 angular or circular draft-flue 9 is formed a partition 11, which closes the flue at that point, the purpose being to divert the draft to determined parts or portions of the contents of the kiln and to prevent it from reaching others. 75 Within the space inclosed by the inner wall of the flue 9 is a flue 8', which may be arranged at right angles to the main draft-flue 12 and communicating therewith at its side, as seen in Fig. 1, or it may be arranged as 80 seen in Fig. 3 and open at its outer end into the main draft-flue. The main draft-flue 12, as shown, opens into the stack 13 at the outer end. In the outer end of the flue 12 is a damper 14, by which the draft through the 90 flue may be regulated to the extent of entirely shutting it off. On each side of the flue 12 is a draft-flue 15 16, opening from the central passage or flue 9 and opening into the stack at their other ends, as shown in Fig. 3 95 of the drawings. In each of the flues 15 16 is a damper 17 18, which regulates the draft therethrough.

It will be perceived from the foregoing description, taken in connection with the drawings, that when the flues 15 and 16 are closed and the main flue 12 is open the draft in the kiln is direct to the center portion thereof; also, that by closing the flue 12 and leaving flue

15 closed and opening flue 16 then the draft is substantially shut off from one half of the kiln, and, further, it will be perceived that if the draft is stopped in flues 16 and 12 and 5 15 left open the other half of the kiln will have the benefit of the arrangement, the advantages following being the complete control of the heat-currents and the closing down of portions of the kiln when the burn is completed, leaving the remaining portions still 10 active, thereby saving fuel and labor and obtaining a thorough and even burn in all portions of the kiln.

In Fig. 3 of the drawings the central flue- 15 passage is shown circular with passages leading therein and the draft-flue section 8' in alinement with the main draft-flue and the floor-flue b, covering the central portion, laid at right angles to the others. The arrangement does not differ materially from the preferred construction illustrated in Fig. 2, and the mode of operation and result are identical.

Having described my invention, what I claim is—
25 1. A brick-kiln having an interior compartment, furnaces arranged in the wall of the kiln and having flues opening adjacent to the top of the kiln, a central flue extending around the middle portion of the base of the kiln and 30 having a partition arranged therein, radial flues opening into the opposite sides of the

central flue, a flue disposed within the space inclosed by the inner wall of the central flue, floor-flues parallel with each other and bridging the central and radial flues, an open-work floor on the parallel floor-flues, and a main draft-flue opening from the flue inclosed by the central flue. 35

2. A brick-kiln having an interior compartment, furnaces arranged in the wall of the kiln and having flues opening adjacent to the top of the kiln, a central flue extending around the middle portion of the base of the kiln and having a partition across it, radial flues opening into the opposite sides of the central flue, 40 a flue disposed within the space inclosed by the inner wall of the central flue, floor-flues parallel with each other and bridging the central and radial flues, an open-work floor on the parallel floor-flues, a main draft-flue 45 opening from the flue inclosed by the inner wall of the central flue, draft-flues on each side of the main draft-flue, and opening from the central flue, and dampers in the main draft-flue and the side flues. 50

In testimony whereof I affix my signature in presence of two witnesses.

CHAUNCEY B. PLATT.
